EDWARD A. CUNNIF, OF THOMPSONVILLE, CONNECTICUT, ASSIGNOR TO BIGELOW-HARTFORD CARPET COMPANY, OF THOMPSONVILLE, CONNECTICUT, A CORPORATION OF MASSACHUSETTS.

PILE-FABRIC EDGE-TRIMMING MACHINE.

Application filed May 2, 1928. Serial No. 274,540.

This invention relates to machines for trimming the edges of textile fabrics and more particularly for trimming the projecting pile threads or fibres along the edges of pile fabrics.

In the production of pile fabrics it is now the common practice to provide a backing fabric of woven material to which the pile loops, either cut or uncut, are secured. The 10 selavage edges of the backing fabric usually present no outwardly extending weft or filling threads, but the pile loops which are secured to the backing fabric during the weaving operation are liable to have portions 15 thereof extending beyond the selavage edges of the backing fabric, a condition which is particularly observable where the pile loops are of the cut variety, and with the result that the selavage edge of the pile fabric is 20 liable to present an uneven appearance.

An important feature of the present invention therefore consists in means for trimming or cutting the laterally projecting pile threads or fibres along the edges of pile fabrics and especially along the selavage edges thereof. In accordance with the present invention, the pile fabric, the edges of which are to be trimmed, is fed and guided longitudinally past cooperating cutters which act 25 upon the pile threads along the edges of the fabric and trim them in a manner to present clean, straight edges to the fabric as a whole.

Since the pile threads or fibres along the edges of the pile fabric may project laterally 30 and downwardly, and consequently not pass into the cutting zone, another important feature of the present invention consists in providing a pile thread lifter which acts upon the edge pile threads as the fabric is fed towards the cutting station to position such pile 35 threads and fibres for the action of the cutters.

Another important feature of the invention 40 consists in cutting mechanism which comprises a stationary or fixed cutter having its cutting edge disposed on or above the upper plane of the backing fabric and a cutter carrier having a plurality of cutting blades which co-operate with the fixed cutter on or above the plane of the upper surface of 45 the backing fabric to trim the pile threads and fibres along the edges thereof.

The invention and new features thereof and novel combination of parts will best be

made clear from the following description and the accompanying drawings of one good 55 form thereof.

In the drawings:

Fig. 1 is a perspective view showing a trimming machine for textile fabrics containing the present invention;

Fig. 1^a is a perspective view of one good form of pile lifter for lifting the pile threads and fibres along the edge of the fabric as it is fed to the cutting mechanism;

Fig. 2 is a plan view at one side of the machine showing the relation of machine parts;

Fig. 3 is a sectional elevation on the line 3-3 of Fig. 2;

Fig. 4 is a detached detail, parts broken away, showing the action of the pile lifter 70 and cutting mechanism; and

Fig. 5 is a vertical section through the pile fabric, and table or support, showing the relation of the cutting mechanism with the pile threads and fibres during the cutting 75 operation.

The machine containing the present invention may be associated with the usual pile shearing machine, if desired, but, as shown in the present instance, the machine of the present invention may be utilized apart from the shearing machine and have the fabric passed therethrough in a separate fabric manipulation.

The frame of the edge trimming machine 85 may be of any usual character and as shown comprises the top plate 1 which may be conveniently supported at each side of the machine by uprights 2, only a part of which is indicated by Fig. 1. Rising from the top plate 1 is a bearing block or support 3, one at each side of the machine, for the appropriate support of the rotary cutter shaft 4 which extends transversely between the bearing blocks 3, and may be driven from any suitable source of power, not shown.

Mounted upon the cutter shaft 4 is the rotary cutter carrier, which in the present instance of the invention, comprises a hub portion 5 mounted on the rotary cutter shaft for adjustment longitudinally thereof. The rotary cutter carrier is preferably splined to the cutter shaft 4, as indicated in Fig. 2, wherein a keyway 6 is formed longitudinally in the rotary cutter shaft 4 for the reception 105 of the key 7 which engages a corresponding

keyway in the rotary cutter, and suitable means, such, for instance, as the securing bolt 8, may be employed for holding the rotary cutter carrier in fixed position on the rotary cutter shaft. It is to be understood, of course, that there is a rotary cutter carrier adjacent each end of the cutter shaft, and by the means described these cutters may be adjusted towards or from each other to adapt 10 the machine for cutting the pile threads and fibres along the edges of fabrics which vary in width.

Each of the rotary cutter carriers is provided with a cutting blade support 9, preferably formed as a hub portion on the inner face of the cutter carriers. The cutter blade support 9 is provided with a series of recesses 10 which extend outwardly at an angle to the radius of the cutter carrier, as indicated in 20 Fig. 3, and in each of the recesses 10 there is supported a cutting blade 11, of which there may be any suitable number. Each of the cutting blades 11 is secured to the blade support 9 to maintain the cutting blades in proper position extending outwardly at an angle to the radius of the rotary cutter, as indicated in Fig. 3, and an appropriate means for thus securing the cutting blades may be constituted by screws 12.

Each of the cutting blades 11 is flared inwardly near the peripheral portion of the cutter carrier, as indicated in Figs. 2 and 3, and has its leading edge portion 13 sharpened to cooperate with the fixed cutter, as will 35 presently be described. The outer edge portion 14 of each of the cutting blades 11 is likewise provided with a sharpened edge, for a purpose presently to be described.

It may become desirable at times to adjust 40 the cutting blades 11 that they may properly cooperate with the fixed cutter, and to this end the cutting blades 11 are formed of spring metal, the outer portion of which, as indicated in Fig. 3, rests against an adjusting screw 15 which may be threaded into the enlarged 45 flange portion 16 of the rotary cutter, and held in place by lock nuts 17, the construction being such that upon loosening the lock nuts, the adjusting screws 15 may be properly 50 manipulated to position the cutting end portion of the cutting blades 11. The described construction of the rotary cutter constitutes a good practical form of the invention, but such 55 rotary cutter and its accessories may be modified and varied within the true scope of the invention, as pointed out by the claims.

Extending between the bearing blocks 3 is a shaft or support 18 to which may be secured in adjusted position transversely of 60 the machine the fixed cutting blade 19, one at each side of the machine.

In the form of the invention shown, the fixed cutter 19 is secured to a hub portion 20 mounted upon the transversely extending 65 shaft or support 18 and adjustable thereon

transversely of the machine and held in adjusted position by a set screw 21, as indicated in Figs. 1 and 3, the result being that the fixed cutting blades may be adjusted transversely of the machine to accommodate 70 fabrics of different widths.

As indicated more clearly in Fig. 3, the fixed cutting blade 19 has a yoke portion 22 which partially embraces the hub 20 and is secured thereto by suitable means, such as 75 the screws 23.

Mounted between the cutting mechanism at each side of the machine is a table or support 24 which may be appropriately secured to the top plate 1 by a bolt 25 which passes through a slot 26 in the top plate 1, so that the support or table 24 may also be adjusted transversely of the machine, it being understood that there is such a table or support 24 at each side of the machine, as indicated in 80 Fig. 1, which constitutes a rest or support for the pile fabric *a* as it is fed between the cutting mechanisms.

Threaded to each of the tables or supports 24 is an adjusting bolt 27, Figs. 1 and 2, the outer end portion of which bears against the side of the fixed cutting blade 19, with the result that it affords a fine adjustment for the fixed cutting blade after the latter has 90 been moved into proper lateral position to suit the width of the fabric to be treated. It is appropriate, also, that the adjusting screw 27 be fixed in position when the parts are finally 95 adjusted, and to this end the adjusting screw 27 is provided with a lock nut 28.

From the construction thus far described, it will be apparent that as the pile fabric *a* is fed through the machine in the direction of the arrow, Fig. 1, the cutting mechanism constituted by the fixed and rotary cutters will 100 act upon and trim threads along the edges of the fabric.

As hereinbefore stated, one of the important features of the present invention consists in trimming the pile threads along the edges of the pile fabric, and since such pile threads may not always be in proper position for the action of the cutters, the present invention provides a pile thread lifter, one at each side of the machine, the purpose of which is to insure that the pile threads projecting along the edges of the fabric may be raised into the cutting zone as the fabric passes over the table or support 24 and past the cutters.

The pile thread lifters for lifting the pile threads and fibres along the edges of the fabric may be variously contrived, but in the present instance each is formed as an arm 29 which extends from the hub 20 backwardly towards a suitable guide roll 30 over which the fabric passes from the source of supply 115 towards the cutting mechanism.

The guide roll 30 may be supported in suitable bearings 31, one at each side of the machine, and is preferably loosely mounted, so 130

that the guide roll 30 may rotate under the pull of the pile fabric.

Each of the arms 29 is provided with a pile lifting portion 32 and a fabric edge guide 33.

- 5 The pile lifting portion 32 is shown as constituted by a gradually rising incline towards the hub 20, the effect being that as the edges of the fabric pass along the edge guides 33, any pile threads which are depressed along the 10 edges will ride over the pile lifter 32 and be raised into the cutting zone of the cutting mechanism. To insure this functional action of the pile lifters, the ends of the arms 29 are provided with a bearing 34 for a pile fabric 15 depressor or rod 35 which extends between the arms 29 and under which the pile fabric passes on its way to the cutting mechanism. The rod or guide 35 may be appropriately secured to the arms 29 by set screws 36.
- 20 As hereinbefore indicated, the purpose of the cutting mechanism is to cut the pile threads and fibres along the edges of the fabric above the backing thereof to provide a clean straight edge thereto, a condition which 25 is more clearly indicated in Fig. 5.

Referring to Fig. 5, it will be noted that the cutting edge 37 of the fixed cutter 19 is disposed in the plane of or slightly above the plane of the upper surface of the backing 30 fabric *b* from which the pile threads project, with the result that the combined action of the fixed and rotary cutters trims the pile threads above the backing fabric *b* as the pile fabric is fed past the cutting mechanism over the supports or tables 24 and without at the 35 same time injuring or cutting the selvage edge of the backing fabric.

Where the machine of the present invention is employed independently of the shearing mechanism some means is desirable for feeding the fabric through the machine, and to this end a spiked roll 38 may be employed to engage the fabric, as indicated in Figs. 1, 2 and 3, and effect its feed longitudinally 45 through the machine. The spiked roll 38 is appropriately driven at the desired speed in the direction of the arrow, as shown in Fig. 1, but since the driving mechanism for the spiked roll forms no essential part of the 50 present invention, the details of such driving mechanism, which may be of usual character, are not illustrated, but will be clearly understood by those skilled in the art.

From the construction described it will be 55 apparent that as the pile fabric is fed through the machine in the direction of the arrow, Fig. 1, it will pass over the guide roll 30 under the rod 35 and its edges will be guided by the guiding surfaces 33 of the arms 29, one at 60 each side of the machine, and as the edges of the fabric pass along the guiding surfaces 33, the projecting pile threads along the edges of the fabric will be engaged by the pile lifters 32 and raised into position for the action 65 of the cutting mechanism, which acts

along the edges of the fabric substantially in the line of or above the upper surface of the backing fabric, to thereby trim and cut any pile threads or fibres which extend beyond the edges of the fabric.

As hereinbefore stated, the cutting blades 11 not only have cutting edges 13 to cooperate with the fixed cutter 19, but the end portion of each cutting blade 11 is also provided with a cutting edge 14 which, as the fabric 75 is moving continuously between the cutting portions of the fixed and rotary cutters, will act upon the projecting fibres with a slicing cut to insure that the entire edge portions of the fabric shall be properly trimmed.

What is claimed is:

1. In a machine for trimming pile threads along the edge of a pile fabric, the combination of a table or support for the pile fabric, means for feeding the pile fabric over the surface of the table or support, a fixed cutter having its cutting edge above the backing of the pile fabric, and a cutter cooperating with the fixed cutter to trim the pile threads projecting above and beyond the edge of the 90 backing of the pile fabric.

2. In a machine for trimming pile threads along the edge of a pile fabric, the combination of a table or support for the pile fabric, means for feeding the pile fabric over the surface of the table or support, a pile thread lifter for raising pile threads along the edge of the pile fabric, a fixed cutter having its cutting edge above the backing of the pile fabric, and a cutter cooperating with the fixed 95 cutter to trim the pile threads projecting above and beyond the edge of the backing of the pile fabric.

3. In a machine for trimming pile threads along the edge of a pile fabric, the combination of a support for the pile fabric, means for feeding the pile fabric over the support, a pile lifter for raising pile threads projecting beyond the edge of the backing fabric as the pile fabric is fed over the support, and 105 cooperating cutters for cutting the pile threads along the edge of the pile fabric.

4. In a machine for trimming pile threads along the edge of a pile fabric, the combination of a support for the pile fabric, means for feeding the pile fabric over the support, a pile lifter for raising pile threads projecting beyond the edge of the backing fabric as the pile fabric is fed over the support, and 115 cooperating cutters having their cutting edges acting above the backing of the pile fabric for cutting the pile threads raised by the pile lifter along the edge of the pile fabric.

5. In a machine for trimming the pile threads along the selvage of a pile fabric, 125 the combination of a support over which the pile fabric is fed, a fixed cutter, means for guiding the pile fabric past the fixed cutter to present pile threads along the selvage of the pile fabric to the cutter, and a rotary cut- 130

ter cooperating with the fixed cutter to trim pile threads along the edge of the pile fabric above the backing of the pile fabric.

6. In a machine for trimming pile threads along the selvage of a pile fabric, the combination of a support over which the pile fabric is fed, a fixed cutter, means for guiding the pile fabric past the fixed cutter to present pile threads along the selvage of the pile fabric to the cutter, a rotary cutter cooperating with the fixed cutter to trim pile threads along the edge of the pile fabric above the backing of the pile fabric, and means for relatively adjusting the cutters laterally towards and from each other.

7. In a selvage edge trimming machine for trimming the pile threads along the edge of the backing fabric, the combination of a fixed cutter, a rotary cutter carrier having a series of cutting blades to successively cooperate with the fixed cutter to trim the pile threads projecting beyond the selvage of the backing fabric, guides for directing the fabric as it is fed past the cutters, and means for independently moving each of the cutting blades laterally on the rotary cutter carrier relatively towards and from the cutting plane of the stationary cutter.

8. In a selvage edge trimming machine for trimming pile threads projecting along the selvage of the backing fabric, the combination of a fixed cutter, a rotary cutter carrier having a series of cutting blades arranged at an angle to the radius of the rotary cutter carrier to cooperate with the fixed cutter, guides for directing the fabric past the cutters, and means for directing the pile threads along the selvage of the backing fabric into the cutting zone above the backing fabric that the surface pile threads extending beyond the edge of the backing fabric may be trimmed.

9. In a selvage edge trimmer for trimming the surface pile threads that project beyond the selvage of textile fabrics, the combination of a fixed cutter, a rotary cutter carrier having a series of cutting blades, each provided with a side cutting edge to cooperate with the fixed cutter and an end cutting edge of substantial extent against which the projecting pile threads are moved as the fabric is fed past the rotary cutters, and means for guiding the fabric to present surface pile fibres along its edge to the action of the cutters.

10. In a selvage edge trimmer for textile

fabrics, the combination of a fixed cutter, a rotary cutter carrier having a series of cutting blades, each provided with a side cutting edge to cooperate with the fixed cutter and an end cutting edge to act independently of the fixed cutter upon and to cut the fibres with a slicing cut as the fabric is fed past the rotary cutters, means for guiding the fabric to present fibres along its edge to the action of the cutters, and a pile thread lifter to act along the edge of the fabric to lift the edge fibres above the edge of the backing fabric into the range of action of the cutters.

11. In a selvage edge trimmer for textile fabrics, the combination of a table or support over which the fabric is fed, a fixed cutter mounted to act upon the fibres above the edge of the backing fabric as it is fed over said support, a rotary shaft having a rotary cutter carrier provided with a series of independently mounted cutting blades, means for securing the cutting blades to the carrier, devices for regulating the cutting relation of the individual cutting blades and fixed cutter, and means for feeding the fabric over the table or support to present projecting edge pile fibres above the backing fabric to the action of the cutters.

12. In a machine for trimming the edges of textile fabrics, the combination of a fixed cutter, a rotary cutter carrier having a series of cutting blades to successively cooperate with the fixed cutter to trim off the surface pile fibres along the edge of the backing fabric, and means acting along the edge of the fabric as it is fed to raise the surface pile fibres which project beyond the selvage of the backing fabric into the field of action of the cutters.

13. In a machine for trimming the surface pile fibres along the edge of the backing fabric, the combination of a table or support over which the pile fabric is fed, cooperating cutters for trimming surface pile fibres that project beyond the edge of the backing fabric, a fabric guide, and a pile lifter which acts on projecting pile fibres along the edge of the backing fabric to progressively raise the pile fibres into the zone of action of the cutters above the edge of the backing fabric.

In testimony whereof, I have signed my name to this specification.

EDWARD A. CUNNIFF.
